UNITED STATES PATENT OFFICE

95,610

DESIGN FOR A STORAGE BATTERY CASE

Oliver O. Rieser, Oak Park, Ill., assignor to The Richardson Company, Lockland, Ohio, a corporation of Ohio

Application March 20, 1935, Serial No. 55,972

Term of patent 7 years

To all whom it may concern:

Be it known that I, Oliver O. Rieser, a citizen of the United States, residing in Oak Park, in the county of Cook and State of Illinois, have invented a new, original, and ornamental Design for a Storage Battery Case, of which the following is a specification, reference being had to the accompanying drawing, forming part thereof.

In the drawing:—

Figure 1 is a perspective view of my novel

storage battery case showing a side and end panel thereof.

Figure 2 is an elevational view of the end panel. The side and end of the storage battery case not shown in the drawing bear substantially the same design as the side and end illustrated.

I claim:

The ornamental design for a storage battery case, as shown and described.

OLIVER O. RIESER.
